JEWELRY TRAY AND REMOVABLE COVER THEREFOR

Erwin Kalla, Pittsburgh, Pa., assignor to Reliable Luggage, Inc., West Pittsburgh, Pa., a corporation of Pennsylvania

Filed Apr. 2, 1965, Ser. No. 84,584

Term of patent 14 years

(Cl. D58—12.7)

FIG. 1 is a front perspective view of the jewelry tray and removable cover therefor with the cover in closed position;

FIG. 2 is a front perspective view of the tray with the cover in an alternate position for use as a mirror;

FIG. 3 is a rear elevational view of the tray of FIG. 2;

FIG. 4 is an end elevational view taken from the right in FIG. 3; and

FIG. 5 is a plan view of the tray on an enlarged scale with the cover removed.

I claim:

The ornamental design for a jewelry tray and removable cover therefor, as shown and described.
